CLAIM

The ornamental design for a lamp module for electronic device, as shown and described.

DESCRIPTION

FIG. 1 is the front perspective view of a lamp module for electronic device showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof; and,

FIG. 7 is the bottom plan view thereof.

The broken lines in the drawings depict parts of the lamp module for electronic device that form no part of the claim.
